Attorney

UNITED STATES PATENT OFFICE.

THOMAS R. BERRY, OF LEAD, SOUTH DAKOTA.

VALVE.

Application filed August 29, 1922. Serial No. 584,968.

To all whom it may concern:

Be it known that I, THOMAS R. BERRY, a citizen of the United States, residing at Lead, in the county of Lawrence and State 5 of South Dakota, have invented certain new and useful Improvements in a Valve, of which the following is a specification.

The present invention relates to an electrically operated valve being constructed especially for use in conjunction with the drain pipe of a radiator or water jacket of an internal combustion engine used upon an automobile so as to prevent, or do away with the necessity of lifting the hood and getting into an inconvenient position for operation of the valve now commonly employed for that purpose. Of course, the valve has other usages to which it may be put without departing from the spirit of 20 this invention.

The principal object of the invention is to provide a device of this character operable by a solenoid, and means being provided for holding the valve either in an open 25 or a closed position after the same has been actuated by the solenoid.

With the above and numerous other objects in view, which will appear as the description progresses, the invention resides 30 in such novel features of construction, combination and arrangement of parts as will be hereinafter more fully described and claimed.

In the drawing:—

35 Figure 1, is a section through the device embodying my invention, and

Figure 2 is a fragmentary section therethrough showing the valve in an open position.

40 Referring to the drawing in detail it will be seen that a valve casing 1 is attached or formed integral with a box like structure 2. A valve seat 3 is arranged on the upper end of the valve casing 1 for receiving puppet 45 valve 4 which is provided with a depending stem 5 projecting through the guides 6. A pin 7 extends transversely through the bottom end of the valve stem 5, and a compressible coil spring 8 is disposed above the 50 stem 5 between the pin 7 and the lower guide 6 so as to normally hold this valve in a closed position upon its seat 3. A bell crank lever 9 is pivoted at 10 one arm thereof being wholly situated within the box like structure 2 while the other arm thereof projects through a slot 11 and engages the

bottom end of the valve stem 5 so that when this bell crank lever 9 is pivoted, it will raise the valve stem 5, thereby lifting the valve 4 from its valve seat 5 and 60 allowing the water to drain from the pipe 12 which is threadedly attached to the valve casing 1. Suitable threads 13 being provided for this purpose. A solenoid 13 is mounted on the box like structure 2 in the 65 end opposite to that to which is attached the valve casing 1, and is provided with the core 14 which is normally held out of the solenoid 13 by a compressible coil spring 15. A pair of arms 16 and 17 are attached to 70 the outer extremity of the armature core 14. The arm 17 has a slotted extension 18 which is engaged by the pin 18' carried by the end of the bell crank lever 9. This arm 17 is provided with a notch 20 on its under edge 75 which is engageable by a spring pressed catch 21 mounted on a spring 22 which in turn is carried by the electro-magnet 23. The other rod 16 is grounded as at 24 and is provided with an insulating strip 25 intermediate its ends on its upper edge which is engageable by the spring contacts 26 and 27 which at all times are in engagement with the upper edge of this arm 16.

At 28 and 29 I have shown diagrammatically ordinary push buttons for operation of the valve. When the push button 29 is depressed, it will be seen that the current flows from the battery 30 through the wire 31 through wire 32, through push button switch 29, through wire 33, through the solenoid 13, through wire 34, through spring contact 27, through arm 16 which is grounded as at 24. The circuit thus closed causes energization of the solenoid 13 pulling inwardly the armature core 14 and compressing the spring 15. As this armature core 14 is pulled inwardly it swings the bell crank lever 9 through the intermediacy of the arm 17 causing the opening of the valve 4 as 100 previously indicated. As the solenoid causes the armature 14 to move, the notch 20 will be engaged by the catch 21 so that when the finger is lifted off of the push button 29, the valve will be held in an open position as is 105 evident. It will also be noted that as the catch 21 engages the notch 20 simultaneously the contact 27 comes into contact with the insulating strip 25, whereby the circuit is broken no matter how long the finger is 110 pressed upon the push button 29.

When it is desired to close the valve 4,

the push button 28 is actuated whereby the current will flow from the battery 30 to the wire 31, through the wire 36, through the push button 28 through wire 37 through 5 the electromagnet 23, through wire 38, through the spring contact 26, through the arm 16 which is grounded. This circuit causes the energization of the electromagnet 23 whereby the catch 21 is attracted thereby 10 causing its disengagement from the notch 20 and allowing the valve to be closed being actuated by the compressed springs 8 and 15 as will be evident from an inspection 15 of the drawings. It is also to be noted that as the armature core 14 is projected out of the armature 13 by the spring 15, the spring contact 26 will be brought into engagement with the insulating strip 25, causing the 20 breaking of this second circuit no matter how long the finger is held upon the push button 28.

It is thought that the construction and operation of my invention will therefore be clearly understood without a more detail description thereof, but it is desired to point out that numerous changes in the construction, and in the combination and arrangement of parts may be resorted to without departing from the spirit of the invention as 30 hereinafter claimed.

Having thus fully described my invention, what I claim is:—

In combination a valve casing, a valve therefor; means for normally holding the 35 valve in a closed position, a lever having one end thereof engageable with the valve, a solenoid including a core movable therein,

a spring for normally holding the core in an extended position; a rod extended from the core and connected with the lever so that upon energization of the solenoid the core will be moved inwardly and the rod actuated to swing the lever for opening the valve, a spring pressed catch, said rod provided with a notch adapted to be engaged by the catch when the valve is in an open position, an electro-magnet associated with the catch which when energized will attract the catch so as to disengage from the notch of the rod, a primary circuit including a switch, a source of electrical energy, the solenoid, a spring contact, a contact rod attached to the core of the solenoid and provided with an insulating strip, said contact rod and said source of electrical energy being grounded, 50 said spring contact being only engaged with the insulated portion of the contact rod when the core of the solenoid is in a retracted position and the valve opened, an auxiliary circuit including the source of electrical energy, a second switch, the electromagnet a second spring contact, and the contact rod, said second contact being only engaged with the insulated strip of the contact rod when the valve is in a closed position so 55 that the electromagnet is always de-energized at this time.

In testimony whereof I affix my signature in presence of two witnesses.

THOMAS R. BERRY.
